PLLC(57) **CLAIM**

An ornamental design for a floating matter remover, as shown and described.

DESCRIPTION

FIG. 1 is a front view of a floating matter remover, showing my new design;

FIG. 2 is a top view thereof;

FIG. 3 is a bottom view thereof;

FIG. 4 is a center cross-sectional view thereof;

FIG. 5 is a cross-sectional view of the floating matter remover in an open position;

FIG. 6 is a top perspective view thereof;

FIG. 7 is a bottom perspective view thereof;

FIG. 8 is an exploded top perspective view thereof;

FIG. 9 is an exploded bottom perspective view thereof; and,

FIG. 10 is a front view of the floating matter remover in an open position.

The back view, right side view and left side view of the floating matter remover is symmetrical to (i.e. same as) the front view shown in FIG. 1.

The broken lines in the drawings illustrate portions of the floating matter remover that form no part of the claimed design. The dash-dot broken lines in FIG. 5 and FIG. 10 illustrate unclaimed environment.
